United States Patent Office

Des. 194,837
Patented Mar. 19, 1963

194,837

OFFICE CHAIR

Clara A. Ridder, Greensboro, and Byron S. Clapp, Siler
City, N.C., assignors to Boling Chair Company, Siler
City, N.C.

Filed Apr. 13, 1962, Ser. No. 69,695

Term of patent 14 years

(Cl. D15—1)

FIG.2

FIG.1

FIG.4

FIG.3

FIG.5

FIG.6

FIG.7

FIG.8

FIGURE 1 is a perspective view illustrating the front and one side of an office chair employing our new design; FIGURE 2 is an elevational view illustrating a side thereof;

FIGURE 3 is an elevational view illustrating the back thereof;

FIGURE 4 is a plan view illustrating the top thereof;

FIGURE 5 is a perspective view of a modified form of the design shown in FIGURE 1, wherein the headrest has been omitted and a slightly lower back cushion has been employed;

FIGURE 6 is an elevational view illustrating a side thereof;

FIGURE 7 is an elevational view illustrating the back thereof; and

FIGURE 8 is a plan view illustrating the top thereof.

The dominant features of the design reside in the features shown in full lines in the drawings and consists primarily in the chair frame and arms, together with the single back support, all as shown.

We claim:

The ornamental design for an office chair, substantially as shown and described.
